Charles G. Hendley

ATTORNEY

UNITED STATES PATENT OFFICE.

JOSEPH R. ALDEN, OF GRAND RAPIDS, MICHIGAN.

SHAVING CUP.

1,404,256.

Specification of Letters Patent.

Patented Jan. 24, 1922.

Application filed March 18, 1919. Serial No. 283,339.

To all whom it may concern:

Be it known that I, JOSEPH R. ALDEN, a citizen of the United States, and a resident of Grand Rapids, in the county of Kent and State of Michigan, have invented certain new and useful Improvements in Shaving Cups, of which the following is a specification.

The object of my invention is to provide a simple and convenient folding or collapsible, combined shaving cup and brush. The device is so constructed that the detachable cover of the cup forms the handle for the shaving brush. The brush and cup are so constructed and arranged that when the brush is detached from the cup and the sections of the cup are collapsed the brush may be dipped into the lower section of the cup in order that the bristles may dip into the water held in the lower section whereas, after the cup has been used the sections are extended and held there so that the brush is held away from the bottom of the cup.

In the drawing forming part of this application:

Figure 1 is an elevation of a shaving cup embodying my invention, showing it in condition for carrying in a bag or kit.

Figure 2 is a vertical sectional view showing the parts in the same position as in Figure 1.

Figure 3 is a horizontal sectional view showing the cup in use and

Figure 4 is a plan view of the cup with the cover removed.

The cup includes a bottom section 1 for holding water or soap and it consists of the bottom 2 and the cylindrical wall 3 extending upwardly therefrom. The section 1 has a bottom flange 4 provided with an internal thread 5 and there is a detachable annular member or ring 6 which is screwed into the threaded flange 4 and which projects at 7 laterally beyond the section 1. The receptacle also includes a telescoping member 8 of cylindrical shape which is adapted to slide up and down over the bottom section 1. In its lowermost position the section 8 is adapted to rest on the projecting portion 7 of the detachable ring 6, as is shown in Figure 3; and I have provided means for holding it in extended or raised position. Preferably, there are projections or beads 9 extending outwardly from the top of the section 1 and these move in vertical grooves 10 in the upper portion 8. At the lower

portion of the section 8 these grooves turn at right angles to form turnouts 11 for the projections 9.

The cover 12 for the receptacle forms the handle for the brush. The cover preferably has a top 13 shaped to provide a convenient grip and it has a flange 14 adapted to abut against the top edge of the section 8. The cover also has a reduced portion provided with the external thread 15 which engages the internal thread 16 in the top section 8. The cover may include a body of rubber 17 or other bristle holding material and the bristles 18 are set in this material so that they hang down within the cup when the cover is in place.

In Figures 1 and 2 the device is shown in condition for packing or carrying in the bag or kit. The section 8 has been raised in relation to the section 1 and also turned so that the projections 9 engage in the groove turnouts 11, and in this position the projections hold the sections from telescoping by keeping them in their extended position. The cover 12 is screwed into the upper section 8 so that it forms a closure for the top of the cup and the bristles are held up out of contact with the bottom of the cup and if there is a cake of soap in the lower section 1 the bristles will be held away from this also. In this condition the bristles are not compressed or bent out of shape and they may dry out in their proper condition.

When the device is to be used the cover 12 is unscrewed from the section 8 and the brush is thus released for use. The section 8 is also turned in relation to the lower section 1 and when the projections 9 come into line with the vertical portions 10 of the grooves the section 8 will drop or it may be moved down until it rests upon the projecting portion 7 of the ring 6. The overall height of the cup has been reduced to about one half and the brush will reach down into the lower section and there reach any water which is placed therein. After the device has been used it is closed and returned to the condition shown in Figures 1 and 2.

The section 8 may be removed at any time by unscrewing the ring 6 and sliding the section 8 downwardly over the lower section 1 until it disengages therefrom. The ring forms a convenient means for maintaining the cup in assembled condition.

The device is simple, convenient and sanitary.

Having described my invention what I claim is:

1. A combined shaving cup and brush comprising a telescoping cup consisting of 5 a cylindrical liquid and soap holding bottom section, a cylindrical upper section adapted to slide in telescoping relation downwardly over said bottom section, means for holding said sections in extended relation, and a removable cover for said upper cup section, provided with bristles to form a brush of which said cover forms the handle, said brush being held away from the bottom of said lower cup section when the 10 cup sections are extended and adapted to extend into said lower cup section when the cup sections are collapsed.
2. A combined shaving cup and brush comprising a telescoping cup consisting of 20 a cylindrical liquid and soap holding bottom section, a member having a threaded connection with said bottom section and projecting laterally beyond the same, a cylind-

rical upper cup section adapted to slide in telescoping relation downwardly over said bottom section and adapted to be retained on the latter by said projecting member, projections on said lower cup section, said upper cup section having grooves to receive said projections, said grooves comprising 25 vertical portions and lateral portions or offsets, a cover having a screw threaded connection with the top of said upper cup section and provided with bristles to form a brush of which said cover forms the handle, 30 said brush being held away from the bottom of said lower cup section when said projections engage in the offset portions of said grooves, and adapted to project into said lower cup section when said upper cup section is lowered over said lower cup section. 35

Signed at the city of St. Paul, county of Ramsey and State of Minnesota, this 28th day of February, 1919.

JOSEPH R. ALDEN.
